M. C. WHITAKER AND A. A. BACKHAUS,
APPARATUS FOR PRODUCING ETHYLENE.
APPLICATION FILED JULY 11, 1919.

1,402,329.

Patented Jan. 3, 1922.

Milton C. Whitaker and Arthur C. Packham, INVENTOR
Pringle, Wright & Small, BY ATTORNEYS

UNITED STATES PATENT OFFICE.

MILTON C. WHITAKER, OF NEW YORK, N. Y., AND ARTHUR A. BACKHAUS, OF BALTIMORE, MARYLAND, ASSIGNORS TO U. S. INDUSTRIAL ALCOHOL CO., A CORPORATION OF WEST VIRGINIA.

APPARATUS FOR PRODUCING ETHYLENE.

1,402,329.

Specification of Letters Patent. Patented Jan. 3, 1922.

Application filed July 11, 1919. Serial No. 310,124.

To all whom it may concern:

Be it known that we, MILTON C. WHITAKER, a citizen of the United States, and a resident of New York city, in the county 5 and State of New York, and ARTHUR A. BACKHAUS, a citizen of the United States, residing at Baltimore, State of Maryland, have invented a certain new and useful Improvement in Apparatus for Producing 10 Ethylene, of which the following is a specification.

Our invention relates particularly to a method of making ethylene by the use of a catalytic agent.

15 The object of our invention is to provide an apparatus by means of which ethylene may be made catalytically and in an expeditious and economical manner.

Another object of our invention is to provide 20 an advantageous apparatus for making ethylene from ethyl alcohol.

A further object of our invention is to provide 25 an apparatus by means of which ethylene may be produced from ethyl alcohol in such a way as to obtain the maximum yield with the utilization of a minimum amount of heat.

Again another object of our invention is to use the apparatus in such a manner as to 30 completely separate the ethylene from the unchanged alcohol.

Still another object is to preheat the alcohol, so as to avoid the presence of liquid alcohol in the chamber where the catalyst is 35 located, in order to avoid loss of the catalyst by the formation of ethyl esters of phosphoric acid.

Further objects of our invention will appear from the detailed description thereof 40 contained hereinafter.

While our invention is capable of embodiment in many different forms, for the purpose of illustration we shall describe only one type of apparatus in the accompanying drawing, in which;

The figure is a diagrammatic elevation of an apparatus made in accordance with our invention.

In the drawings, we have shown a pipe 50 1 adapted to conduct hot gases, which may be heated gases derived from any source, as for example from an oven or furnace, said heated gases being conducted by the pipe 1

to a furnace 2 having removable top and bottom plates 3 and 4. The furnace 2 is 55 provided with a plurality of vertical tubes 5 supported by two tube sheets 6 and 7, and carrying within their passages a catalyst adapted to form ethylene from alcohol. The ethylene-forming catalytic material 60 may be comprised of a quantity of comminuted coke or pumice stone carrying phosphoric acid (H_3PO_4), or instead, if desired, carrying finely divided aluminum oxide or kaolin. Preferably the tubes are 65 filled with comminuted coke and the phosphoric acid is then poured into the tubes so as to be absorbed by the comminuted material in the tubes. The hot gases after passing around the tube 5, leave the furnace 2 by a pipe 70 8, and thence pass into and downwardly within an alcohol preheater 9 through a plurality of tubes 10 therein, supported by tube sheets 11 and 12, after which the hot gases are conveyed away by a stack 13. The alcohol is fed to the apparatus from an alcohol supply tank 14 by means of valved trapped pipe 15 to the alcohol preheater 9, where the ascending alcohol is immediately converted into a vapor which passes from the preheater 9 by a pipe 16 to the lower end of the furnace 2. The alcohol vapors are conducted upwardly through the tubes 5 in the furnace 2, where the alcohol is converted to a very large extent into ethylene and water. 85 The vapors of ethylene, alcohol and water leave the top of the furnace 2 by means of a pipe 17, and are conducted to a column heater 18 where they serve to heat a body of water to provide steam for a column 19, the 90 excess water from which is preferably allowed to continually flow away by a pipe 20 connected to the heater, and which leads to a discharge pipe 21 delivering into a funnel 22, whence the water may be conveyed away 95 to any point of disposal. A pipe 23 equalizes the pressures in the pipe 20 and the upper part of the heater 18. The heater 18 is comprised of a plurality of tubes 23^a supported by tube sheets 23^b and 23^c. The 100 vapors from the heater 18 pass out by a pipe 24, and are shown to be conducted to a hot alcohol condenser 25 having a plurality of tubes 26 supported by tube sheets 27 and 27^a therein, around which the vapors flow. 105 The condenser 25 serves the purpose of re-

moving the major portion of the alcohol and water from the ethylene, so that the alcohol may be returned to the system while warm. From this point, the vapors pass by a pipe 5 27^b to a cold alcohol condenser 28 having a plurality of tubes 29 supported by tube sheets 29^a and 29^b around which said vapors are caused to flow, so as to remove the residual alcohol and water, and allow the purified ethylene gas to pass out by a pipe 30, whence the ethylene may be collected and utilized in any desired manner. The alcohol and water containing a very little ethylene are returned by pipes 31 and 32 from the 10 condensers 28 and 25 respectively to the column 19. As the vapors pass upwardly through the column 19, the liquid contained in the pans in said column becomes increasingly richer in alcohol, and from the top of 15 said column the alcohol is fed by a pipe 33 to the alcohol preheater 9. The gases and vapors which reach the top of the column 19 pass out of the same by a pipe 34, and thence into a hot condenser 35 having a plurality of tubes 36 supported by tube sheets 37 and 38, from which point the condensed alcohol is conveyed by a pipe 39 to the top of the column 19, so as to provide liquid for sealing the pans in said column. From the 20 hot condenser 35 the gases and vapors passing out of the same are conducted by a pipe 40 to a cold condenser 41 having a plurality of tubes 42 supported by perforated plates 43 and 44, while the residual gases and 25 vapors not condensed therein are conveyed away by a pipe 45 to the pipe 27^b. The condensate from the condenser 41 is conveyed by a pipe 46 to the pipe 39, and thence to the top of the column 19. The condensers 28 30 and 25, and 41 and 35, may be maintained at the desired temperatures in any suitable manner. For example, the condensers 28 and 25 may be cooled by a current of water passing through pipes 47, 48 and 49, and the 35 condensers 41 and 35 may be cooled by a current of cold water passing through pipes 50, 51 and 52.

In carrying out our invention in the described apparatus, the following procedure may be followed:—Alcohol is supplied from the tank 14 through the preheater 9 maintained at a temperature of from 300 to 500° C., and to the furnace 2 which is also maintained at a temperature of from 300° 55 to 700° C., where the alcohol vapors formed in the preheater 9 are changed in part to ethylene and water by contact with the phosphoric acid or other catalyst present in the furnace 2. From this point the vapors of ethylene, alcohol and water pass to the column heater 18 where they serve to provide steam for the alcohol concentrating column 19. The ethylene, alcohol and water vapors pass from the column heater 60 65 18 to the hot and cold condensers 25 and 28,

whence the condensed alcohol and water containing a little ethylene is conveyed back to the column 19, while the effluent ethylene passes out of the condenser 28 in the form of a gas, and may be collected and used in any desired manner. The concentrated alcohol produced in the column 19 is fed therefrom to the preheater 9. Alcohol to fill the pans of the column 19 is supplied to the column by pipes 39 and 46 leading 75 from the condensers 35 and 41 through which the vapors from the top of the column 19 pass, and from which condensers any quantity of ethylene present is conveyed away to the condenser 28 where any remaining percentage of alcohol and water is removed from the ethylene, and the ethylene becomes added to the main body thereof, so that all of the ethylene is thus recovered at the outlet end of the condenser 80 85 28 separated from the alcohol and water.

In this manner the ethylene is recovered after the alcohol and water have been entirely separated therefrom, while at the same time the heat of the various compounds present is utilized throughout the operation of the apparatus, and in such a manner that the apparatus may be operated continuously. Furthermore, the catalyst is utilized to the best advantage as the formation of ethyl compounds thereof is avoided. 90

While we have described our invention above in detail, we wish it to be understood that many changes may be made therein without departing from the spirit thereof. 100

We claim:

1. An apparatus for manufacturing ethylene comprising the combination of a catalytic chamber containing a catalyst, a preheater connected to the chamber, means for heating the preheater and chamber, an exit conduit leading from the chamber to a compartment in the bottom of a rectifying column and an exit conduit leading therefrom to a condenser, a condensing system connected to the top of the rectifier, return flow conduits leading from said system to the rectifier, return flow conduits leading from the above mentioned condenser to the rectifier, a supply conduit leading from the rectifier to the preheater, a supply tank and a conduit leading therefrom to the preheater. 105 110 115

2. An apparatus for manufacturing ethylene comprising the combination of a catalytic chamber having tubes containing a catalyst, a preheater connected to the chamber, means for heating the preheater and tubes, an exit pipe making communication between the tubes, a heating compartment in the bottom of a rectifying column and an exit conduit leading therefrom to a condenser, a condensing system connected to the top of the rectifier, return flow conduits leading from said system to the top of the rectifier, return flow conduits leading from the 120 125 130

above mentioned condenser to the rectifier, a supply conduit from the top of the rectifier to the preheater, a supply tank and a conduit leading therefrom to the preheater.

- 5 3. An apparatus for manufacturing ethylene comprising the combination of a catalytic chamber having tubes containing a catalyst, a preheater connected to the chamber, means for heating the preheater and tubes, an exit conduit making communication between the tubes and a heating compartment in the bottom of a rectifying column and an exit conduit leading therefrom to a condenser, a condensing system connected to 10 the top of the rectifier, return flow pipes leading from said system to the rectifier, return flow conduits leading from the above mentioned condenser to the rectifier, a supply conduit leading from the top of the rectifier to the preheater, a supply tank and a conduit leading therefrom to the preheater, and a conduit connecting the discharge of the condensing system to the above mentioned condenser so that residual gases from the 15 condensing system can be passed over to the condenser and condensed therein.

4. An apparatus for manufacturing ethylene comprising the combination of a catalytic chamber having tubes containing a catalyst, a preheater connected to the chamber, means for heating the preheater and tubes, an exit conduit making communication between the tubes and the heating compartment in the bottom of the rectifying column 30 and an exit conduit leading therefrom to a condenser, a condensing system connected to the top of the rectifier, said condenser and condensing system each comprising a hot and a cold condenser for vapors, return flow conduits leading from said condenser and condensing system to the rectifier, a supply conduit leading from the rectifier to the pre- 35

heater, a supply tank and a conduit leading therefrom to the preheater.

5. An apparatus for manufacturing ethylene comprising the combination of a catalytic chamber containing a catalyst, a preheater connected to the chamber, means for heating the preheater and chamber, an exit conduit leading from the chamber to a condenser, a rectifier, return flow conduits leading from the condenser to the rectifier, and a supply conduit leading from the rectifier to the preheater. 45

6. An apparatus for manufacturing ethylene comprising the combination of a catalytic chamber containing a catalyst, a preheater connected to the chamber, means for heating the preheater and chamber, an exit conduit leading from the chamber to a condenser, a rectifier, return flow conduits leading from the condenser to the rectifier, a supply conduit leading from the rectifier to the preheater, and separate means for supplying alcohol to the preheater. 50

7. An apparatus for manufacturing ethylene comprising the combination of a catalytic chamber containing a catalyst, a preheater connected to the chamber, means for heating the preheater and chamber, an exit conduit leading from the chamber to a condenser, a rectifier, return flow conduits leading from said condenser to the rectifier, a condensing system connected to the top of the rectifier, return flow conduits leading from the system back to the rectifier, and a supply conduit leading from the rectifier to the preheater. 65

In testimony that we claim the foregoing, we have hereunto set our hands this 3rd day 70 of July, 1919.

MILTON C. WHITAKER,
ARTHUR A. BACKHAUS.
